UNITED STATES PATENT OFFICE.

FRANZ LAWACZECK, OF AERZEN, NEAR HAMELN, GERMANY.

TURBINE COMPRESSOR OR PUMP FOR ELASTIC FLUIDS.

1,047,663.

Specification of Letters Patent. Patented Dec. 17, 1912.

Application filed May 22, 1911. Serial No. 628,726.

To all whom it may concern:

Be it known that I, FRANZ LAWACZECK, a citizen of the German Empire, residing at Aerzen, near Hameln, in the Kingdom of Prussia, Germany, have invented certain new and useful Improvements in Turbine Compressors or Pumps for Elastic Fluids; and I do hereby declare the following to be a full, clear, and exact description of the invention, such as will enable others skilled in the art to which it appertains to make and use the same.

My invention relates to improvements in turbine compressors or pumps for fluids.

15. In compressors or blowers of the centrifugal or turbine type, in which the pressure of the fluid at the outlet is subject to considerable variations, the volume of fluid forced through the discharge is considerably increased when its pressure is reduced. This increase in the volume of fluid results in an increase of the energy consumed by the compressor. Furthermore, in many cases the volume of the fluid supplied by the compressor must be constant, even if the resistance of the fluid varies. For example, where the compressor is used to supply combustion air to high furnaces, cupola furnaces, and other fire places, the volume of the air must always be constant, while its pressure is of minor importance, provided it is so high that it can always force the necessary amount of combustion air through the fuel. In order to keep under such circumstances the volume 35 of the air constant, regulating means, such as throttle valves, have been provided which were set either manually or automatically according to the resistance of the furnace or other place of use.
40. The object of my improvements is to provide a compressor of the class indicated in which special regulating means are dispensed with, and in which the regulation of the volume of the fluid supplied by the compressor is effected by the construction of the machine itself, and more particularly by the construction and arrangement of the vanes of the impeller and especially of the guiding apparatus.
45. Broadly speaking my invention consists in so constructing the vanes, that upon a reduction of the resistance of the fluid within the discharge conduit or place of use, and therefore upon an increase of the volume of the fluid supplied by the compressor, the loss 50 caused by the impact of the fluid upon its

discharge from the impeller and its admission to the guide vanes and the contraction thereof within the guide passages are such, that the resistance of the fluid within the 60 guide passages is sufficiently increased, as to prevent an undue increase in the volume of the fluid supplied by the compressor.

For the purpose of explaining the invention an example embodying the same has 65 been shown in the accompanying drawing in which the same letters of reference have been used in all the views to indicate corresponding parts.

In said drawing—Figure 1, is a partial 70 section of the guide apparatus of the compressor taken perpendicularly to the axis of the compressor, and showing two guide blades providing a guide passage for the fluid and illustrating, in a diagrammatical way, the relative speeds of the fluid entering the guide passage and of the impeller. Fig. 2, is a similar section showing the actual contraction or reduction of the cross-sectional area of the steam passing through the guide 75 passage caused by a decrease in the resistance and an increase in the speed of the fluid; Fig. 3, is a similar section of the impeller and the guide or diffusion apparatus, Fig. 4, is a cross-section taken on a plane 80 through the axis of the compressor, Figs. 5 and 6 are detail views showing the manner of securing the side wall ring on the impeller, and Figs. 7 and 8 are further views showing the manner of mounting the vanes on the 85 impeller.

As is known to those skilled in the art, when the volume of the fluid forced by the impeller of a turbine compressor differs from that for which the vanes of the impeller and the guide apparatus and the passages formed by said vanes have been designed, a loss by impact is being caused in the flow of the fluid upon the passage of the latter from the impeller to the guide apparatus. If the volume is above the normal, the angle between the tangent of the impeller and the direction of flow at which the air is discharged from the impeller is larger than that between the tangent and the vanes of the diffusion or guide apparatus. Furthermore, as is indicated in Fig. 2, the current of the fluid is contracted within the passages of the guiding apparatus.

My invention consists in using these facts, 110 i. e. the loss caused by impact and the contraction of the current of fluid, for regu-

lating the compressor. And with this object in view my invention consists in so arranging the vanes of the guiding apparatus, that the loss by impact and the contraction 5 of the fluid are sufficient to hold the volume of fluid supplied by the compressor within definite limits.

I have found, that for the same relative increase of the volume of the fluid the loss 10 caused by the impact of the fluid at its discharge from the impeller attains its maximum, if the angle ς at the inlet of the vanes of the guiding apparatus is about 45 degrees, or if $\operatorname{tg}\varsigma$ is about equal to 1, as appears 15 from the following: If for the normal value of the volume of fluid the radial component of the speed of the current of air at the discharge from the impeller is v_r , this value is increased to $v_r(1+p)$, if the volume is increased 20 $p\%$. At the normal output the angle of the current discharged from the impeller will be ς . If the output is increased $p\%$ the increase of the said angle will be α . The value of this increased angle is

$$25 \quad \operatorname{tg}(\varsigma + \alpha) = \frac{v_r(1+p)}{u},$$

in which equation u is the circumferential speed of the impeller which is constant. As 30 $\operatorname{tg}\varsigma$ is equal to $\frac{v_r}{u}$, I have the following equation:

$$35 \quad \frac{\operatorname{tg}(\varsigma + \alpha)}{\operatorname{tg}\varsigma} = 1 + p.$$

If this equation is reduced, I have

$$tg\alpha = \frac{ptg}{(1+p)\operatorname{tg}\varsigma^2 + 1}$$

40 Obviously the value $tg\alpha$ is a direct measure of the value of the impact. If the increase of the angle $d(tg\alpha)$ is considered as a function of $d(\operatorname{tg}\varsigma)$, it will be found by differentiation, that for the constant change of the 45 volume of $p\%$ this increase attains its maximum at a value of

$$tg\alpha = \sqrt{1+p};$$

50 in our case p will ordinarily be a small value, because only a small variation in the output is desired. Therefore the most favorable value of the angle at the inlet of the vanes of the diffusion apparatus is about 55 45° , and the effect of the impact used for regulating the compressor is so much the larger, the nearer the said angle is to the value of 45° . Therefore comparatively large radial speeds are favorable for regulating 60 the compressor. The throttling which can thus be obtained will ordinarily not be sufficient for properly regulating the output of the compressor, and it is necessary to make use of the contraction of the current 65 of the fluid. To make this contraction suf-

ficient it is but necessary to provide a sufficiently large number of vanes in the diffusion apparatus, or to make the relative distance of the said vanes sufficiently small. Obviously the said contraction will be the 70 same for each vane, so that the remaining area is so much the smaller, the smaller the relative distance of the vanes is. These conditions will readily be understood from an inspection of Fig. 2 in which a guide passage is shown, the direction of the current of air which enters the said passage corresponding to an increase of the output above the normal. If the air enters the said passage without any impact, that is under normal conditions, the cross-sectional area through which the air can flow will have the value $t \sin. \varsigma$. If the volume of air is increased, the said area will be reduced to the value $t \sin. \varsigma - m$. Therefore the coefficient of the contraction will be

$$\varphi = 1 - \frac{m}{\sin. \varsigma}$$

If the number of the vanes is increased 90 and therefore the value t is decreased, for example to $\frac{1}{2} t$, the coefficient of the contraction is increased to

$$95 \quad - \frac{2m}{t \sin. \varsigma}.$$

The derivation of the value m from the actual direction of the flow of the fluid or, what is the same, from the percentage of the increase of the volume above the normal output, can easily be ascertained by experiment. If thereafter it is prescribed, for a certain installation, that in case of a variation of the resistance the increase of the 100 volume of fluid will be not more than $p\%$, the value t which is necessary to meet this condition can be calculated from the values m and ς .

Experience has shown, that in turbine 110 compressors the energy required is substantially proportional to the volume of the fluid forced by the compressor. Therefore, when using my improved self-regulating turbine compressor the required energy can 115 not be increased more than $p\%$.

As far as practical construction of the compressor is concerned, it will be remembered, that ordinarily in case of fluid admission to the diffusion apparatus without impact the efficiency is increased, if the number of the vanes is increased, because thereby whirls of the fluid are prevented. If however the number of the vanes is too high, the said efficiency will fall again by reason 120 of the increase in the friction of the fluid on the vanes which in constructions now in use are not sufficiently smooth. Besides, it is necessary to sharpen the vanes as far as possible, if their number is very large. 125

For this reason in my improved turbine compressor in which the number of the vanes is considerably above what is now common in machines of this class the vanes 5 are preferably made of polished band steel of a thickness of about $\frac{1}{4}$ of a millimeter, and they are preferably bent into shape within the compressor itself by being clamped between suitably fashioned blocks. 10 Therefore it is not necessary to bend the said vanes prior to mounting the same in the compressor which would more or less impair their smoothness. By thus constructing the vanes I have guide passages for the 15 air, the walls of which are exceedingly smooth, and which can be sharpened to any degree of sharpness, so that under the normal output of the compressor and admission of the fluid into the vanes without impact the efficiency is high notwithstanding the large number of the vanes.

To show my improved construction more in detail an example thereof has been shown in Figs. 3 to 8 of the drawings. Though 25 my improved construction of the vanes is particularly useful in combination with the construction of the compressor described above, I wish it to be understood, that my invention is not limited to such use, and that 30 my improved vanes may be used in compressors of the ordinary form in which self-regulation is not aimed at.

Referring now more particularly to Figs. 3 to 7 of the drawings, the casing *e* and the impeller *d* are provided with annular dovetailed notches *k* and *k'* respectively within which corresponding clamping blocks *a* and *b* are fitted which are fashioned according to the curved forms of the vanes *c* and *c'* 40 of the guiding or diffusion apparatus and the impeller. The said vanes, which are made of elastic highly polished steel bands, are bent into their proper form by being clamped between the blocks *a* and *b*.

45 Ordinarily the vanes are held in position by friction. However where the speed of the impeller is high I prefer to secure the vanes against being thrown outward by centrifugal force, for which purpose I provide pins *f* which are passed through bores of the vanes *c'* and with their projecting ends are engaged in notches *n* of the clamping blocks *b*, as is shown in Figs. 7 and 8.

The clamping blocks can be manufactured 55 at low cost and with great accuracy on molding machines. They can receive a high polish, so that the friction of the fluid flowing between the vanes is reduced to a minimum. Even for high speeds they may be 60 made of cast iron or aluminum, because they are not subjected to tensile strains.

If it is desired to cover the vanes *c'* of the impeller by a ring *h*, as is shown in Figs. 5 and 6, the said ring is secured in 65 place by stay bolts *i* which are covered by

steel bands, which are secured in place by suitable clamping blocks. Thereby whirls are prevented in the passages of the impeller.

While in the preferred form of the invention both regulating means, *i. e.* regulation by impact and regulation by contraction, are provided in the same turbine compressor, I wish it to be understood, that my invention is not limited to such combined use of both regulating means, and that in many cases regulation either by impact or by contraction may be found sufficient. It should also be understood, that my invention is not limited to a single stage blower, 75 or to the constructions shown in the drawings.

While in describing the invention reference has been made to turbine pumps for elastic fluids in which automatic regulation 85 is particularly important, I wish it to be understood that my invention is not limited to pumps of this field of use, and that my improved automatic regulation will also be useful in pumps for non-elastic fluids, such as 90 water.

I claim herein as my invention:

1. In a fluid compressor or blower of the turbine type, the combination with an impeller, of a guiding apparatus interposed 95 between said impeller and the outlet of the compressor or blower, and provided with a plurality of guide vanes, said vanes being arranged at such angle to lines tangent to the impeller and being located at such distance apart that in case of a decrease of the resistance at such outlet to the discharge of the fluid therefrom, the currents passing between the vanes will be contracted to afford a resistance corresponding with the resistance at such outlet. 100

2. In a fluid compressor or blower of the turbine type, the combination with an impeller, of a guiding apparatus, provided with vanes; the angle at which said vanes are inclined to the tangent of said impeller being such that a line indicating the resultant of the radial and tangential forces, touching the inner edge of one of said vanes will pass through the space between two adjacent vanes at a distance from both of said vanes, the vanes being at such distance apart that in case of a variation in the resistance at the outlet of the compressor or blower, the current of fluid flowing between such adjacent vanes is so contracted or expanded as to afford a resistance corresponding with the resistance at such outlet. 110

3. In a fluid compressor or blower of the turbine type, the combination with an impeller, of a guiding apparatus, provided with vanes, each of said vanes at the inlet of the impeller being inclined at an angle of approximately 45° to the tangent of the impeller, and the distance apart of such vanes 125

being such that in the case of a decrease of the resistance at the outlet of the compressor or blower, the current of fluid is retarded by impact and is contracted in passing through the passages between the vanes to such an extent as to afford a resistance corresponding with the resistance at such outlet.

5. In a fluid compressor or blower of the turbine type, the combination with an impeller, of a guiding apparatus, provided with curved vanes, the angle between the tangent to the impeller and the tangent to said vanes at the inlet from the said impeller being approximately 45°.
10. 6. In a fluid compressor or blower of the turbine type, the combination with an impeller, of a guiding apparatus, provided with thin, curved, sheet metal vanes; the curvature of and distance between said vanes being such that in case of a decrease of the resistance at the outlet of the compressor or blower the current of the fluid is contracted during its passage between said vanes to such an extent as to afford a resistance corresponding with the resistance at such outlet.
15. 7. In a fluid compressor or blower of the turbine type, the combination with an impeller, of a guiding apparatus, provided with curved vanes made of band steel and 30 clamping blocks having curved clamping faces between which the side margins of said vanes are confined and by which the desired curved form is given to said vanes.
20. 8. In a fluid compressor or blower of the turbine type, the combination with an impeller, of a guiding apparatus interposed between said impeller and the outlet of the compressor or blower, and provided with a plurality of guide vanes, said vanes being 40 arranged at an angle to lines tangent to the impeller and located at such distance apart that in case of a decrease of the resistance at such outlet to the discharge of the fluid therefrom, the currents passing between the 45 vanes will be contracted to afford a resistance corresponding with the resistance at such outlet.

turbine type, the combination with an impeller, of a guiding apparatus, provided with curved vanes made of band steel and 30 clamping blocks having curved clamping faces between which the side margins of said vanes are confined and by which the desired curved form is given to said vanes.

7. In a fluid compressor or blower of the 35 turbine type, the combination with an impeller, of a guiding apparatus interposed between said impeller and the outlet of the compressor or blower, and provided with a plurality of guide vanes, said vanes being 40 arranged at an angle to lines tangent to the impeller and located at such distance apart that in case of a decrease of the resistance at such outlet to the discharge of the fluid therefrom, the currents passing between the 45 vanes will be contracted to afford a resistance corresponding with the resistance at such outlet.

In testimony whereof I affix my signature in presence of two witnesses.

FRANZ LAWACZECK.
